US00D420100S

United States Patent [19]

Sato et al.

[11] Patent Number: Des. 420,100

[45] Date of Patent: ** Feb. 1, 2000

[54] **MANIFOLD FOR SOLENOID-OPERATED DIRECTIONAL CONTROL VALVE**

[75] Inventors: **Hideharu Sato; Takumi Matsumoto**,
both of Ibaraki, Japan

[73] Assignee: **SMC Corporation**, Tokyo, Japan

[**] Term: **14 Years**

[21] Appl. No.: **29/094,746**

[22] Filed: **Oct. 9, 1998**

[30] **Foreign Application Priority Data**

Apr. 13, 1998 [JP] Japan 10-10531

[51] LOC (7) Cl. **23-01**

[52] U.S. Cl. **D23/233**

[58] Field of Search D23/233-236,
D23/245-248; 137/596.13, 596.16, 625.64,
884

[57] **CLAIM**

The ornamental design for manifold for solenoid-operated directional control valve, as shown and described.

DESCRIPTION

FIG. 1 is a top, front and right side perspective view of manifold for solenoid-operated directional control valve embodying our new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a top, front and left side perspective view thereof, shown in use with a solenoid transfer valve which is shown in broken lines and forming no part of the claimed design.
